DEVICE TO PRODUCE A STRAIGHT LINE OR MULTIPLE OF LINES ON A TYPEWRITER

Armando Dal Molin, New York, N. Y.

Application April 21, 1953, Serial No. 350,066

4 Claims. (Cl. 197—113)

This invention relates to typewriters and more particularly to a device for producing a straight line or a multiple of straight lines on a typewriter.

It is the principal object of the present invention to provide a device which will produce a straight horizontal line or a plurality of straight horizontal lines in parallel spaced relation to each other and of any predetermined thickness or combination of thicknesses like border lines, of a ruled-like quality, much improved over the standard underscores and borders produced on a standard typewriter in the conventional manner by striking repeatedly a key bearing a type with the desired lines on it.

It is another object of the present invention to provide a device of the above type which may be readily and easily installed on conventional typewriters to permit the typing of a straight horizontal line or a plurality of straight horizontal lines in parallel spaced relation to each other.

It is still another object of the present invention to provide a device of the above type which may be used to permit the typewriter to type a plurality of parallel spaced straight lines across the paper to represent the staff of a musical score.

Another object of this invention is to provide a standard typewriter with a general means of obtaining a perfectly placed impression, devoid in the resulting writing of misalignment or misprints of characters due to the springing action of the type bars occurring while the type bar travels from the idle position to the point of impact on the roller of the typewriter, said general means consisting of dividing the typing action in two distinct operations; the first being to bring the selected key in striking position by pressing the correspondent key on the keyboard, the second being to impart to the key standing very close to the paper an additional blow by means of a hammerlike separated key to provoke the impression on the paper.

Other objects of the present invention are to produce a device bearing the above objects in mind which is of simple construction, inexpensive to manufacture, has a minimum number of parts, is easy to use and is efficient in operation.

For further comprehension of the invention and of the objects and advantages thereof, reference will be had to the following description and accompanying drawings, and to the appended claims in which the various novel features of the invention are more particularly set forth.

Since this invention covers all different types of typewriters, the means of accomplishing the aforesaid device are slightly different with each make of typewriter. The following drawings cover the part of the invention applicable to all standard typewriters:

Fig. 1 is a fragmentary front perspective view of a typewriter showing the present invention in operative use thereon.

Fig. 2 is an enlarged fragmentary perspective view of the parts comprising the invention.

Fig. 3 is a view similar to Fig. 2 but showing a modi-

2

fied form of the invention having a different shape of the back portion of the type bearing the lines to show how to avoid having a separate hammer key.

Fig. 4 is a front elevational view of two different type-bars bearing different types of lines.

Fig. 5 is a diagrammatic view of the present invention showing a variation of same with reference to typewriters having the ribbon feed actioned by means of a universal bar.

10 Fig. 6 is a fragmentary perspective view of the front row of keys on a standard typewriter modified to make room for the underscore key.

Referring now more in detail to the drawing, in which similar reference numerals identify corresponding parts 15 throughout the several views, there is shown in Fig. 1 a typewriter 10 of conventional construction including the platen roller 11, the type-bar guide 12 and the segment 13, substantially as illustrated. The usual standard ribbon carrier 14 is provided behind the guide 12 and receives the typewriter ribbon in a manner well known to those skilled in the art.

A type 18 is provided and carries a plurality of print lines 19, the lines 19 being parallel to each other and vertically spaced apart as shown in Fig. 4. The lines 19 25 are carried on the striking face 20 of type 18 and are adapted to strike to a common printing center at or about the horizontal center line of the platen roller 11. Five of these parallel lines may be used to type the staff of a musical score.

The type 18 is provided with a slot 21 which receives the upper portion of type-bar 15, as shown in Fig. 2. The type 18 is secured in the above position by means of rivets 22 or simply by soldering.

A hammer 27 is provided with a slot 28 which receives the upper portion of type-bar 25, substantially as illustrated in Fig. 2, the hammer 27 being secured to the type-bar 25 by means of rivets 29 or by welding.

The type-bar 25 and the hammer 27 thereof normally rest in a horizontal position in the circular type basket, 40 along with the other keys, not shown.

The particular key which causes the type-bar 25 to strike will be appropriately marked to correspond to the straight line markings of type 18.

As shown in Figs. 1, 2 and 5, upon striking the key, 45 the hammer 27 will strike the rear end of type 18, causing the lines 19 to impress themselves on the paper through the ribbon.

A special case that enters the scope of this invention occurs with typewriters having the ribbon feed actioned by means of a universal bar. In this case, it is necessary to keep the ribbon in front of the type 18 all the time and yet to leave the universal bar working at the same time to feed the ribbon through the action of the hammer key as shown in Fig. 5. A pin 23 is attached to the type-bar 15 that engages in the slot 24 in the ribbon carrier 14 of the typewriter. The type 18 is lifted by pressing the key as usual. The ribbon carrier 14 is brought up manually to engage the pin on the bar with the slot in the ribbon carrier.

60 In this case, the ribbon moves through the standard ribbon carrier 14 upon actuation of a lever 30 (see Fig. 5), the means of moving the lever 30 being set back into a notch 31 cut out of type-bar 15, so that the lever 30 is in a non-working condition when the type-bar 15 is in the operative position.

With this construction, the ribbon will move only on the movement of the hammer key or type-bar 25, which is not provided with a slot and which therefore engages the lever 30 upon upward movement to the striking position. Thus, the ribbon will move each time the hammer 27 strikes the back of type 18.

Thus, the depression of the "straight line" key causes

a conventional lever, not shown, carrying a pin engaging with the slot or opening 32 in the bottom of type-bar 25 causing the latter to swing upward toward the horizontal center line of the platen roll 11 and causing the rear end of type 18 to receive the impact of hammer 27.

Thus, a plurality of straight lines, parallel and spaced from each other will be printed on the paper. Such lines are frequently needed in addition to the conventional type characters and by providing them on the typewriter, a printing economy will be effected.

Five of such vertically spaced lines may be provided, as shown in the drawing, forming thereby the staff of a musical score.

Should it be desired to print a lesser or greater number of lines 19 on the paper, another head 18^a may be substituted for the head 18.

As shown in Fig. 4, the head 18^a is provided with a border on upper case, made up of thin line 34 and thick line 35, and a single underscore line 36 on lower case.

In other respects the type head 18^a is similar to the type head 18 and like reference numerals identify corresponding parts throughout the several views.

Thus, to type a plurality of lines from one side of the paper to the other, the straight line type-bar 15 will be raised to the operative position by steadily pressing its appropriate key 33 (see Fig. 6).

The key actuating type bar 25 will then be struck successively, causing the hammer 27 to hit the rear end of head 18 each time the key is struck. The result will be an even, smooth plurality of parallel and spaced lines from one side of the page to the other. Should a border or underscore be desired, the head 18^a will, of course, be substituted for the head 18.

It will be readily seen that the type-bars 15 and 25 may be easily connected to standard machines, or if desired, the head 18 and hammer 27 may be substituted for type carried by any of the conventional type bars.

The above device can be applied to both standard, round platen and flat platen, and the hammer key can be operated either manually or electrically.

The relative position of the type-bar 15 and hammer-bar 25 are not necessarily as in the drawing. They can be anywhere on the segment 13. It is advisable to have the type-bar 15 as close to the center of the basket as possible. The standard placing of the underscore type-bar 11, for example, is ideal. The hammer-bar 25 can be anywhere, even an additional type-bar at either end of the segment. When different lines than the plain underscore are wanted, a separate type is necessary. To keep this bar at the center of the keyboard a rearranging of the front line of keys is preferable, as shown in Fig. 6, the key 33 controlling type 18. For specialized work type 18 can be interchangeable with others preset for the typewriter, thus allowing an infinite possibility of different lines. Fig. 4 shows two types of type, 18^a with an underscore on the lower case and a border on the upper case, and 18, a type for drawing a music staff suited for a music writing typewriter. These types can also be "flat," to be used on flat platen machines such as Elliott Fisher, Music Writer, and Keaton-type typewriters, etc.

The type 18 is not standardly shaped. It has a protruding part in the back to present a striking surface to the hammer-key 25, (Fig. 2). The shape of this back portion can be large (Fig. 2) or fairly small (Fig. 3). The first shape (18 and 18^a) is to be used in conjunction with a hammer-bar 25 (Fig. 2). The second shape 18^b is to be used when using a regular type-bar 37 as a hammer instead of a bar with a hammer shaped head (Fig. 3). This latter arrangement requires very slight change in the standard machine, while at the same time, it allows for a good underscore.

The protruding pointed part 38 is located in such a way to clear the engraving (between the two periods) of a standard type and hit in the blank space between the upper case 39 and the lower case 40 of a type 41.

This latter arrangement is only advisable for the underscore and for light work, since the impact has the tendency of loosening up the type used as hammer. To obviate this to a certain extent, it is advisable to equip both the type 18^b with lines and the type 41 used as hammer with rivets 22 to increase strength.

The type-bar 15 must be "dead" or disconnected from the spacing mechanism. This is a standard possibility for any typewriter and does not enter in the scope of this invention. In operation, simply press with one hand the underscore (or special) key 33 keeping it steadily down while striking repeatedly with the other hand the hammer key until line is completed. In electric typewriters the underscore key has to be adjusted in such a way as to keep it up against the paper until key is released. A repetitive key should be used for the hammer.

This invention also can be extended to cover a machine where "all" the keys are operated by a hammer key as described above for special purposes. The only difference is that "all" the keys will be exactly as key 15. The striking of the hammer key can be made automatic in an electric machine by actioning the tripping mechanism of the hammer key to the universal bar, or to the segment itself or in many other ways outside the scope of this invention.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a typewriter including type-bars, a ribbon carrier, a ribbon and a ribbon actuating lever, a type fixedly carried by the upper end of one of the type-bars, said type on its striking face carrying at least one straight type line, and a hammer fixedly carried by another of the type-bars at the upper end thereof and adapted to strike the rear face of said head, whereby to strike at least one continuous line across the page upon successive actuations of the type-bar carrying said hammer, and a hook carried by the type-bar carrying said type head, the typewriter ribbon carrier having an opening adapted to releasably receive the end of said hook when said carrier is raised whereby to retain the ribbon in an operative position.

2. In a typewriter including type-bars, a ribbon carrier, a ribbon and a ribbon actuating lever, an enlarged type fixedly carried at the upper end of one of the type bars, said type having a striking face at its end adjacent the platen, a plurality of substantially parallel, horizontal, vertically spaced straight type lines provided in said striking face, the rear end of said type remote from the platen protruding toward the type basket, and a hammer head fixedly carried on the top of another of the type-bars and adapted to strike the protruding end of said type successively whereby to type a plurality of vertically spaced lines across the paper from side to side, and a hook below said type head connected to the type-bar, the typewriter ribbon carrier below the guide comb having an opening adapted to releasably engage the end of said hook when said carrier is raised, whereby to retain the ribbon in an operative position.

3. In a typewriter including type-bars, a ribbon carrier, a ribbon and a ribbon actuating lever, a type fixedly carried by the upper end of one of the type-bars, said type on its striking face carrying at least one straight type line, the end of said type remote from its striking face being reduced and adapted to be received between the upper and lower case type of any one of the other types whereby to strike at least one continuous line across the page upon successive actuations of any of the keys of the typewriter, and a hook carried by the type-bar carrying

said type head, the typewriter ribbon carrier having an opening adapted to releasably receive the end of said hook when said carrier is raised whereby to retain the ribbon in an operative position.

4. The combination of claim 2, wherein said type comprises five lines and four spaces to reproduce a musical staff.
